UNITED STATES PATENT OFFICE

2,470,113
FURNITURE

Harry Sebel, London, England

Application April 3, 1946, Serial No. 659,291
In Great Britain January 28, 1946

2 Claims. (Cl. 155—194)

1

The present invention relates to furniture and more particularly to seats and chairs.

Heretofore seats of chairs of the upholstered type have comprised either a rigid support as in the ordinary wooden chair or metal chair or a wholly flexible support such for example as a deck chair.

An object of the invention is to provide a chair which whilst not having the unyielding quality of a rigid seat and back support has not the undesirable flexibility of a deck chair.

A chair according to the present invention includes a frame provided with suitable legs in which is suspended a support of sheet metal or other semi-stiff material for example moulded plywood, synthetic sheet material or the like, the support being suspended to the frame at the top and bottom only.

According to a further feature of the invention the chair according to the present invention is constructed so that it may be stacked, the feature being that there is a clear space on either side of the body support between this support and the frame enabling easy stacking. Other features of the invention will be apparent from the following description of the accompanying drawings in which:

Figure 1 shows in perspective a chair in accordance with the present invention.

Figure 2 shows on a large scale a detail of one method of supporting the seat portion on the frame,

Figure 3 shows a section on the line III—III of Figure 2,

Figure 4 shows a detail of the connection between the frame members of the chair,

Figure 5 is a cross section on the line V—V of Figure 4,

Figure 6 shows a detail of an alternative method of suspending the seat portion,

Figure 7 is a section on the line VII—VII of Figure 6, and

Figure 8 shows how the chair shown in Figure 1 can be stacked vertically.

Referring to the drawings Figure 1 shows a chair in which the frame is formed from metal tube, for example steel tubing. The frame is constructed from two lengths of tubing one length being formed into a U to form combined front legs and back frame 1. The other length of tubing 2 is also formed into a U to form the back legs 3 and the seat frame 4. The portion forming the seat frame 4 preferably is bent above the point at which the two members cross.

The member 2 is formed into a narrower U

than the portion 1 so that it passes between the legs of the member 1, the two being joined as shown in Figures 4 and 5 by a junction piece 5 which may be welded to each leg. The angle at which the two members are joined is such that the chair legs 3 and 6 incline at the same angle to the floor. Ferrules 7 are provided at the bottom of each leg these ferrules conveniently being of rubber or other elastic material so as to deaden the noise made by movement of the chair.

The chair frame is provided with arms or lugs 8 which may be welded in position on the frame and formed from semi-circular pressings the ends of which are conveniently formed with flats 9 which are apertured to receive a nut and bolt 10. The sides of the member 8 are conveniently flattened at 11 so that the nut is prevented from turning when the bolt is turned.

Onto the arms or lugs 8 is suspended a seat portion 12 which is pressed from sheet steel or other suitable material into a proper shape and is apertured so that it may be attached to the arms or lugs 8 by the nuts and bolts 10. In between the seat portion 12 and the arms 8 there is interposed a rubber or other composition washer 13 which insulates the seat from the frame. To finish the seat portion 12 and to improve the peripheral strength when the seat is formed from sheet metal the edge is turned back to form a hem 14.

By suspending the seat portion to the frame only at the top and bottom it gives sufficiently to the user to provide comfort and at the same time it remains substantially rigid laterally bending or yielding only in the longitudinal direction.

This chair can be stacked very easily and by forming the frame so that the frame members where they cross are inclined at the same angle to the floor upon which the chair rests the stacking is truly vertical; this is clearly shown in Figure 8 which shows two chairs stacked together. It will be seen that provided this is so the legs may be curved or otherwise shaped outwardly away from the enclosed angle between them and the seat and back frames may similarly be curved or bent outwardly from the enclosed angle between them where they cross and the chairs may still be stacked vertically.

Figures 6 and 7 show an alternative method of fixing the chair portion 12 to the frame in which it is hooked to the arms or lugs 8, a key-hole aperture being formed in the arcuate seat member 12 which engages with a round-headed pin 15 riveted or welded to the ends of the arms or lugs 8.

Both methods shown in Figures 2 and 6 provide an easy and rapid method of removing the seat portion 12 so as to enable it to be replaced or repaired.

The construction of a chair in accordance with the present invention necessitates a minimum of assembly work and enables easy transport together with the ability of assembling any colour combination of seat and frame. Furthermore, owing to the vertical stacking the height to which the chairs may be stacked is limited only by the vertical space available.

What I claim is:

1. A chair of the stacking type comprising a pair of inverted U-shaped members forming the frame and legs of said chair, one of said members having its legs at a wider spacing than the other of said members and positioned outwardly of the respective legs of said other member and extending in crossing relation thereto, said legs at each side of said chair being rigidly joined at their points of crossing by connecting members the exterior dimensions of which are wholly confined within the spaces between said legs at the crossings thereof, and a laterally bent sheet of self-sustaining springy material attached at its opposite ends to the U-shaped members at the closed ends thereof and being free of attachment along its side edges, said sheet also being laterally spaced from the sides of the back-supporting portion of said frame to provide for passing the legs of narrower spacing of a similar chair between the lateral edges of said sheet and the

5

sides of said back-supporting portion to permit stacking said chairs in vertically superposed relation.

2. A chair as defined in claim 1 in which said U-shaped member having its legs at the narrower spacing is bent forward and downwardly adjacent the bend of the U in a plane at an angle to the plane of the portions thereof which extend in crossing relation to the U-shaped member having legs at wider spacing, the plane of said bent portion extending generally parallel to the plane of the seat of the chair.
